UNITED STATES PATENT OFFICE.

EUGENE PETERS, GEORGE E. BAUDER, AND ALEXANDER D. CAMPBELL,
OF SEATTLE, WASHINGTON.

CONCENTRATOR.

No. 828,963.

Specification of Letters Patent.

Patented Aug. 21, 1906.

Application filed March 5, 1906. Serial No. 304,162.

To all whom it may concern:

Be it known that we, EUGENE PETERS, 5
GEORGE E. BAUDER, and ALEXANDER D.
CAMPBELL, citizens of the United States, re-
siding at Seattle, in the county of King and
State of Washington, have invented certain
new and useful Improvements in Concentra-
tors, of which the following is a specification,
reference being had therein to the accom-
panying drawings, in which—

Figure 1 is a longitudinal vertical section
of apparatus embodying our invention. Fig.
2 is a perspective view of the riffle-frame
shown detached, and Fig. 3 is a cross-sec-
tional view taken through 3 3 of Fig. 1.

This invention relates to concentrators,
and more particularly to apparatus employed
for the separation of the more valuable metal-
liferous particles from mill-tailings or aurif-
erous sands and gravels.

The object of the invention is the provision
of simple and economically-constructed
means whereby the separation and saving of
the precious metals are accomplished with but
25 little waste and with a relatively small con-
sumption of water.

With these ends in view the invention con-
sists in the novel construction, adaptation,
and combination of parts, as will be herein-
30 after described, and pointed out in the ap-
pended claims.

Referring to the drawings, A represents a
chute made desirably rectangular in cross-
section, as shown, and arranged upon sup-
35 ports, such as B, to have a slope downwardly
toward the delivery end. At the receiving end
of the chute is a hopper C, having a discharge-
opening C' with a vertically-slidable gate D
for wholly or partially closing such opening.
40 Positioned above the hopper is a trough E,
having in its bottom a riddle or grizzly E' for
separating the coarse stones from the mate-
rial being treated and allowing only the
smaller screened particles thereof to fall into
45 the hopper accompanied by water.

F is a riffle-frame of a width adapting it to
be placed within the said chute and desirably
of such length as to extend from a cleat B at
the discharge end of the chute to within the
50 opening C' of the hopper, whereat the oppos-
ing faces e and f are inclined, as shown, to af-
ford an interstice therebetween for the inser-
tion of a packing-piece G, of rubber or other
suitable material, and provide a non-leakable

joint. The said frame is comprised of a top 55
F' and sides F'' and is provided interiorly with
alternately-disposed riffles H and deflecting-
bars K. Of these the riffles are disposed at
suitable intervals apart and extend upwardly
from a plane projected through the lower 60
edges of the sides F'' to within a short dis-
tance of the under side of the top F', while
the bars extend downwardly from the latter
and are of less depth than the frame sides.
This frame is likewise provided with a slid- 65

able gate L in proximity of its discharge end.
M is a coarse woven fabric, of burlap or the
like, which is laid in the bottom of the chute
and retained in place by the riffle-frame rest-
ing thereupon.

The material operated upon is supplied to
the trough E, into which water flows, and, as
before stated, is screened by the riddle, caus-
ing only the finer portions of the material, to-
gether with the water, falling into the hopper, 75
whence it flows in a commingled state through
the said chute and riffle-frame. This stream
by being intermittently diverted by the suc-
cessive action of the riffles and bars assumes
an undulating course which affects the heavier 80
metals or concentrates, being entrapped by
the riffles or underlying fabric. By the em-
ployment of the deflector-bars the extremely
fine particles or float-gold is repeatedly pre-
cipitated downwardly to be collected as afore- 85

said.

Should the riffle-frame from any cause be-
come choked, then the water will rise in the
hopper until its head or pressure is capable
of dislodging the obstructions, and by ma- 90
nipulating the said gates the action of the ap-
paratus may be adjusted to meet a variety
of conditions due to the quality of the mate-
rial being handled or the normal pressure or
quantity of the water available.

To clean the apparatus, the gate D' is first
closed and the riffle-frame removed from the
chute, when upon opening this gate the con-
centrates can be washed down to the chute-
cleat for removal.

As is obvious, the operation of the inven-
tion is accomplished by the flow of water, and
its efficiency is due to the undulating course
imparted thereto. There are no parts of the
apparatus liable to get out of order, and the 105
only attention needed is to not overcharge
the receiving-hopper and the proper adjust-
ment of the gates according to the demand.

Having described our invention, what we claim as new, and desire to secure by Letters Patent, is—

1. In an apparatus of the class described, the combination with a chute having a cleat at its delivery end and a hopper provided with a discharge-opening communicating with the chute, and a gate for controlling the discharge through said opening, of a frame 5 movably mounted within said chute, with its outer end bearing against said cleat and its inner end received in the discharge-opening of the hopper, whereby said frame is held down by the hopper, said frame embodying 10 sides and a top, with alternately-disposed riffles and deflector-bars arranged in different planes, the deflector-bars engaging the top of the frame and the riffles being free from engagement with the top of said frame, and a 15 fabric layer on the bottom of the chute and on which the riffles of the frame rest.
2. In apparatus of the class described, the combination with the chute having a cleat at its delivery end, and a hopper provided 20 with a discharge-opening communicating with the chute, of a frame adapted to be placed within said chute with its outer end engaging said cleat and its inner end extending into said discharge-opening, said frame 25 being formed with sides and a top with alternately-disposed riffles and deflector-bars which are arranged in different planes, a layer of fabric intermediate the frame and the bottom of the chute, and a gate for said 30 discharge-opening.
3. In apparatus of the class described, the combination with the chute having a cleat at 35

its delivery end, and a hopper provided with a discharge-opening communicating with the chute, of a frame adapted to be placed within said chute with its outer end engaging said cleat and its inner end extending into said discharge-opening, said frame being formed with sides and a top with alternately-disposed 40 riffles and deflector-bars which are arranged in different planes, a layer of fabric intermediate the frame and the bottom of the chute, a gate for said discharge-opening, and a gate for the delivery end of the frame.

4. In apparatus of the class described, the combination with the chute having a cleat at its delivery end, and a hopper provided with a discharge-opening communicating with the chute, of a frame adapted to be placed within said chute with its outer end engaging said cleat and its inner end extending into said discharge-opening, said frame being formed with sides and a top with alternately-disposed 45 riffles and deflector-bars which are arranged in different planes, a packing-piece 50 for making a non-leakable joint between the hopper and the frame, a layer of fabric intermediate the frame and the bottom of the chute, a gate for said discharge-opening, and a gate for the delivery end of the frame.

In testimony whereof we affix our signatures in presence of two witnesses.

EUGENE PETERS.

GEORGE E. BAUDER.

ALEXANDER D. CAMPBELL.
